MAXIMILIAN MATHIAS, OF BERLIN, GERMANY, ASSIGNOR TO SIEMENS & HALSKE AKTIENGESELLSCHAFT, OF SIEMENSSTADT NEAR BERLIN, GERMANY

AUTOMATIC TELEPHONE SYSTEM

Application filed March 31, 1932, Serial No. 602,137, and in Germany May 29, 1931.

This invention relates to automatic telephone systems in which connections of different value are set up. The object of the invention is to forcibly cut off such speaking connections which can be renewed at any time without loss of time and without extra charge, this being achieved by switching devices provided for limiting the duration of calls being caused to function by means which denote the value of the connections only when the lines are engaged for connections of low value.

An embodiment of the invention is shown in the drawing.

15 In this drawing a subscriber T_{n1} is shown to have access over a preselector VW , allocated to him, to a common group selector, for example IGW . The subscriber, by sending out impulses, is in a position to set this 20 group selector to a further group selector, for example, IGW , and this latter device to a final selector, for example, LW . The subscriber T_{n2} may then be reached by the transmission of two additional impulse 25 series actuating the final selector LW .

The exchange is also provided with a time switch which serves the purpose of cutting off the speaking connection after a definite time period.

30 All the speaking connections, however, are not to be forcibly cut off but only those which the subscriber may set up again without any great loss of time. Connections which take a considerable time to complete (such as, for 35 example, waiting for a toll call to be completed) are not to be cut off.

Each individual subscriber in the embodiment is provided with a time switch for this purpose. Arrangements may also be made 40 to the effect that this time switch is accessible to a large number of subscribers by, for example, associating the switch with the junction line.

45 The type of connections generally outlined above are in detail completed in the following manner: When the subscriber T_{n1} lifts his receiver, relay R is energized over: earth, battery, resistance W_{11} , contact $1t$, subscriber T_{n1} , contact $3t$, relay R , earth. The closing 50 of contact $17r$ sets up an impulse circuit for

the rotary magnet $D1$ of the preselector VW as follows: earth, battery, d-wiper of the preselector VW , contacts $17r$, $16t$, rotary magnet $D1$, relay interrupter $RU1$, earth. The rotary magnet is intermittently influenced in 55 this circuit, causing the preselector to be advanced step by step until it reaches an idle succeeding group selector, for example, IGW . When this occurs the following circuit will be closed: earth, battery, d-wiper of the pre- 60 selector VW , contact segment, contact $17r$, windings II and I of relay T , c-wiper of the preselector VW , contacts $18b$, $20v$, off-normal contact $21k$ of the group selector IGW , winding I of relays A and B , earth. 65 Relay T is energized in this circuit and brings the preselector to rest by opening its contact $16t$. The locking circuit for winding I of relay T is closed at contact $15t$. In the above-mentioned circuit relays A and B 70 also are energized and are maintained energized by means of their winding II over the subscriber's line loop after contacts $2t$ and $4t$ have been closed. The short circuit for relay C is removed by the opening of contact $18b$, 75 with the result that this relay is energized in the locking circuit for relay T and is made independent of the off-normal contact $21k$ of the group selector IGW due to the closing of contact $19c$. Relay C , in addition, actuates 80 its contacts $28c$, $35c$, $40c$, $41c$, and $44c$.

When the subscriber now transmits additional impulses for the setting of the group selector IGW , that is to say, intermittently breaks the locking circuit for relays A and B , 85 the vertical magnet H of the group selector IGW is intermittently energized according- 90 ly and lifts the switch wipers of the group selector to the desired level. This energiz- 95 ing circuit extends over: earth, contacts $26a$, $28c$, winding III of relay V , contact $32d$ of the rotary magnet D , rotary off-normal contact $33w$ of the group selector IGW , vertical magnet H , battery, earth. Relay V also is energized in this circuit and remains ener- 100 gized during the impulse series since it operates as a slow acting relay due to the short-circuit of its winding II . Relay V is released at the end of the impulse series with the result that the rotary magnet D is ener-

gized in the following circuit, the off-normal contact 23k of the group selector IGW having been closed on the first vertical step: earth, battery, rotary magnet D, contact 22v, 5 off-normal contact 23k, contact 25p, earth. The group selector moves one step and, by the closing of contact 31d causes winding II of relay V to be energized over the vertical magnet H of the group selector which, however, is 10 not energized during this operation. The rotary magnet of the group selector is re-energized when contact 22v is opened, and therefore breaks the circuit of relay V at 31d. Should the reached line be busy, the rotary 15 magnet is re-energized after relay V falls back and advances the group selector a further step. This interaction between relay V and the rotary magnet D continues until the group selector has reached an idle succeeding second 20 group selector. Should this group selector happen to be the shown group selector IIGW, the following circuit is completed: earth, contacts 35c, 36a, windings II and I of relay P, c-wiper of the group selector IGW, relay C1, 25 battery, earth. Relays P and C1 are energized in this circuit. The closing of contact 37p causes the high resistance winding II of relay P to be short-circuited which thereby guards the group selector against further seizures. Contacts 42p and 43p switch through 30 the speaking leads to the group selector IIGW.

The subscriber Tn1 is now able to set the 35 second group selector IIGW in a manner of no interest in this case by transmitting an additional impulse series. This group selector IIGW then hunts for an idle final selector, for example LW. The subscriber can influence this also by sending out two impulse 40 series and finally reach the required subscriber Tn2 over said final selector.

The speaking connection is thus completed 45 between the subscribers Tn1 and Tn2 after the appropriate switches have been set, ringing current applied, and the subscriber Tn2 has answered.

The time switch TS has, in the meantime, been caused to function due to the fact that the following circuit of relay Bo was closed 50 when relay T was energized: earth, battery, relay Bo, off-normal contact 13ko of the time switch, contact 14t, earth. Relay Bo is placed in a locking circuit independent of the above-mentioned off-normal contact due to 55 the closing of contact 12bo. The rotary magnet TS of the time switch is set to the contact bank of a 15-second switch by the actuation of contact 11bo. Since the switch wiper of the 15-second switch comes into contact with 60 the said contact every 15 seconds, the switch magnet TS of the time switch is accordingly energized every 15 seconds so that the time switch advances step by step at 15 seconds intervals. The time switch is provided with 65 twenty-three contacts and takes about five

minutes to complete one revolution. When the time switch reaches the last, that is to say, the 23rd contact position, the off-normal contacts 5k23 and 8k23 are closed. The closing of the off-normal contact 5k23 is of no importance for the setting up of these connections. The off-normal contact 8k23 merely applies earth potential to the lower lead of the pre-selector VW. This causes winding II of relay B, in the group selector IGW, to be short-circuited so that this relay releases and brings about the release of relay C, due to the closing of contact 18b. Relay C short circuits winding I of relay P at contact 44c with the result that relay P is de-energized and restores the group selector IGW as well as the additional impulse receivers IIGW and LW to normal, in a manner of no interest in the present case. The existing connection is accordingly cut off after the elapse of a definite period.

In order to advise the subscriber of the expected disconnection, a busy signal may be sent out from the time switch when set to the penultimate contact.

If, however, the subscriber is engaged in a call which requires considerably longer time to be completed than ordinary calls, that is to say, for example, a toll call, this connection should not be cut off. The individual operations are then as follows:

By depressing the key T1, an operator at the operator's position FP seizes a toll final selector FLW and thereby causes relay C1 to be energized over: earth, key T1, off-normal contact 47k1 of the toll final selector FLW, winding II of relay C1, battery, earth. Relay C1, by the closing of contact 46c1, prepares a locking circuit for the further formation of the connecting route. When the operator transmits impulses for the setting of the toll final selector, relay A1 is intermittently energized in the following circuit due to the actuation of the key T2 during the first impulse series: earth, battery, relay A1, key T2, earth. The vertical magnet of the toll final selector FLW is accordingly intermittently actuated over: earth, battery, vertical magnet H, rotary off-normal contact 50w1 of the toll final selector FLW, contact 52u, winding II of relay V1, contact 48a1, earth. Relay V1 also is energized in this circuit and remains energized during the impulse series due to the short circuit of winding I. Relay V1 releases at the end of the impulse series and causes relay U to be energized in the circuit extending over the off-normal contact 59k1 which has been closed in the meantime: earth, off-normal contact 59k1, contacts 58v1, 57c1, winding III of relay U, rotary off-normal contact 50w1 of the toll final selector FLW, vertical magnet H, battery, earth. The vertical magnet H is not energized in this circuit. The closing of contact 51u switches over the rotary magnet D of the toll final selector

- FLW so that the succeeding impulse series actuates this rotary magnet and causes it to be set to the required contact. This impulse circuit extends over: earth, battery, rotary magnet D, contacts 55p1, 51u, winding II of relay V1, contact 48a1, earth. Relay V1 remains energized during the impulse series also in this circuit but releases at the end of said impulse series. Relay U, however, being a slow-acting relay remains energized an extended period due to being maintained during the impulse output over: earth, contacts 68c1, 67u, 66v1, winding I of relay U, battery, earth. The following test circuit is now completed: earth, contacts 68c1, 67u, 65v1, windings II and I of relay P1, c-wiper of the toll final selector FLW, c-wiper of the preselector VW, windings I and II of relay T, d-wiper of the preselector VW, battery, earth. Relays P1 and T are energized in this circuit. By the closing of contact 70p1, relay P1 places its winding I in a locking circuit as contact 67u is now open due to the release of relay U. Relay V1 is re-energized by a five-second switch over its winding III in the following circuit: earth, battery, rotary magnet D, contacts 56p1, 62y, winding III of relay V1, contact 64u, five-second switch, earth. On each energization of relay V1 the ringing machine RM is connected up to a speaking lead over contact 73v1 and, due to the speaking leads being switched through at contacts 74p1 and 75p1, causes the bell at the subscriber's station Tn1 to operate.
- When the subscriber answers, relay Y is energized over the subscriber's line loop and, by opening its contact 62y, prevents a fresh energization of relay V1. At the same time, however, a locking circuit for relay P1 is closed at contact 63y over: earth, battery, rotary magnet D of the toll final selector FLW, contacts 56p1, 63y, winding III of relay P1, key T1 at the operator's position Fp, earth. The rotary magnet D is not energized in this circuit and relay P1 remains energized. Relay Bo is re-energized on the energization of relay T in a similar manner over contact 14t and, by closing its contact 11bo, connects up the switch magnet TS, of the time switch, to the contact of the 15-second switch. The time switch is advanced in the manner described above and on reaching the last contact applies an earth potential over the off-normal contacts 5k23 and 8k23. A toll call being involved in the present instance, this earth potential does not cause the release of the existing connection. Applying earth potential at contact 8k23, however, short circuits windings II of relay Y but this relay still remains energized over its winding I and the short circuit of winding I of relay P1 at the off-normal contact 5k23, which would release the switch in ordinary calls, has no influence in this case due to relay P1 remaining energized over its winding III, even after its winding I has been short-circuited. The time switch, therefore, may leave the last contact without cutting off the connection and return to its original position. The disconnection only takes place when the subscriber has finished the toll call. The release of the connection is carried out by the operator at the toll operator's position in a manner of no interest in this case.
- What is claimed is:
1. In a telephone system, a subscriber's line, a timing device individual to the line, means for establishing two classes of connections with the line, and means controlled by the timing device for automatically releasing connections of one class after a predetermined time but not connections of the other class. 75
  2. In a telephone system, a line, a timing device individual to the line, means for establishing incoming or outgoing connections of one class with the line, means for establishing incoming connections of a different class with the line, and means controlled by said timing device for releasing either incoming or outgoing connections of said one class after a predetermined time but not incoming connections of said different class. 80
  3. In a telephone system, a line, a timing device associated with the line, means for establishing local and toll connections with the line, means for initiating the operation of said device responsive to the establishment of a connection, and means controlled by said device for releasing the connection after a predetermined time provided the connection is a local one. 85
  4. In a telephone system, a line, a timing device associated with the line, means for establishing local and toll connections with the line, means for initiating the operation of said device responsive to the establishment of a connection, means controlled by said device for applying a potential to one conductor of the line after a predetermined time, and means responsive to said potential for releasing the connection provided the same is a local one. 90
  5. In a telephone system, a line, a timing device associated with the line, an automatic switch, means including said switch for establishing a connection with said line, a control relay in the switch energized to maintain the connection, and means controlled by said device for deenergizing said relay after a predetermined time. 95
  6. In a telephone system, a line comprising two talking conductors, a branch of said line comprising two talking conductors and a test conductor, a timing device associated with the line, means for establishing outgoing connections from the line independent of said branch, means for establishing incoming connections to the line over said branch, and means controlled by said device for applying a potential to one of the talking conductors 100
  7. In a telephone system, a line comprising two talking conductors, a branch of said line comprising two talking conductors and a test conductor, a timing device associated with the line, means for establishing outgoing connections from the line independent of said branch, means for establishing incoming connections to the line over said branch, and means controlled by said device for applying a potential to one of the talking conductors 105
  8. In a telephone system, a line comprising two talking conductors, a branch of said line comprising two talking conductors and a test conductor, a timing device associated with the line, means for establishing outgoing connections from the line independent of said branch, means for establishing incoming connections to the line over said branch, and means controlled by said device for applying a potential to one of the talking conductors 110
  9. In a telephone system, a line comprising two talking conductors, a branch of said line comprising two talking conductors and a test conductor, a timing device associated with the line, means for establishing outgoing connections from the line independent of said branch, means for establishing incoming connections to the line over said branch, and means controlled by said device for applying a potential to one of the talking conductors 115
  10. In a telephone system, a line comprising two talking conductors, a branch of said line comprising two talking conductors and a test conductor, a timing device associated with the line, means for establishing outgoing connections from the line independent of said branch, means for establishing incoming connections to the line over said branch, and means controlled by said device for applying a potential to one of the talking conductors 120
  11. In a telephone system, a line comprising two talking conductors, a branch of said line comprising two talking conductors and a test conductor, a timing device associated with the line, means for establishing outgoing connections from the line independent of said branch, means for establishing incoming connections to the line over said branch, and means controlled by said device for applying a potential to one of the talking conductors 125
  12. In a telephone system, a line comprising two talking conductors, a branch of said line comprising two talking conductors and a test conductor, a timing device associated with the line, means for establishing outgoing connections from the line independent of said branch, means for establishing incoming connections to the line over said branch, and means controlled by said device for applying a potential to one of the talking conductors 130

of the line and to said test conductor to release either type of connection.

7. In a telephone system, a line, a timing device individual to the line, a branch of the line comprising two talking conductors and a test conductor, means for establishing connections of two classes with the line over said branch, means including said device for applying a potential to said test conductor a predetermined time after the connection is established, and means operative provided the connection is of one class for releasing the connection responsive to said application of potential.

15 In witness whereof, I hereunto subscribe my name this 1st day of March, 1932.

MAXIMILIAN MATHIAS.
